(57) **CLAIM**

The ornamental design for a rockable platform, as shown and described.

DESCRIPTION

FIG. 1 is a top perspective view of a rockable platform showing my new design;

FIG. 2 is an enlarged bottom perspective view of the rockable platform;

FIG. 3 is a top view of the rockable platform; and,

FIG. 4 is a bottom view of the rockable platform;

FIG. 5 is a side elevational view of the rockable platform, the right and left sides being mirror images of one another;

FIG. 6 is an end elevational view of the rockable platform, the two ends of the rockable platform being mirror images of one another;

FIG. 7 is a side elevational view of the rockable platform shown in condition of use; and,

FIG. 8 is a side elevational view of the rockable platform shown in condition of use.

The broken lines illustrate environmental structure and portions of the rockable platform which form no part of the claimed design.
